FIG. 5

INVENTOR

Jacob Yanow
Ralph Koenig ATT'Y.

BY -

UNITED STATES PATENT OFFICE.

JACOB YANOW, OF ST. LOUIS, MISSOURI, ASSIGNOR TO GRAM HEADWEAR MFG. COMPANY, OF ST. LOUIS, MISSOURI, A CORPORATION OF MISSOURI.

CAP.

1,396,985.

Specification of Letters Patent.

Patented Nov. 15, 1921.

Application filed January 18, 1921. Serial No. 438,133.

To all whom it may concern:

Be it known that I, JACOB YANOW, a citizen of Russia, residing at the city of St. Louis, State of Missouri, have invented a certain new and useful Improvement in Caps, of which the following is a specification, reference being had to the accompanying drawing, forming a part thereof.

This invention relates generally to headwear and, more particularly, to a certain new and useful improvement in caps, the principal object of my present invention being to provide a cap with a readily and conveniently attachable and detachable section for covering and protecting the ears and back of the head, whereby the cap may be convertibly worn with comfort as a head-covering only or ordinary cap in clement, mild weather, and as a head and ear covering in inclement, cold weather.

With the above and other objects in view, my present invention resides in the novel features of form, construction, arrangement, and combination of parts hereinafter described and afterward pointed out in the claims.

In the accompanying drawings.

Figure 1 is a perspective view of a cap equipped for the attachment of the separable ear-and-neck protecting-section, the latter being omitted;

Fig. 2 is an enlarged detail view of the ear and neck protecting-section;

Fig. 3 is a perspective view of the cap with the separable ear and neck protection-section attached;

Fig. 4 is an enlarged detail sectional view of the cap and attached separable ear and neck protecting section taken approximately on the line 4—4, Fig. 3; and

Fig. 5 is a similar view taken approximately on the line 5—5, Fig. 3.

Referring now more in detail to the said drawing, which illustrates a practical embodiment of my invention, and in which like reference characters refer to like parts throughout the several views, the cap proper comprises a body-portion 10, which may be of any suitable flexible material, and which is preferably inturned or folded upon itself at its lower margin, as at 10^a. Disposed within and extending substantially around the body-portion 10 at its margin, as best seen in Fig. 1, is a flat tubular band 11 inclosing a flat strip of buckram or other suit-

able stiffening material 12, the band 11 and its stiffening strip 12 being fixed together and to the flexible body-fold 10^a by preferably spaced longitudinal rows of thread-stitches 13. Sewed or otherwise fixed to the cap-body 10 and reinforced or stiffened band 11, is a front vizor 14, which may be of any usual or approved form; and formed through the band 11 and its stiffening strip 12 on opposite sides of the cap and preferably adjacent the opposite inner ends of the vizor 14, are transverse openings or apertures 15—15 preferably of elongated button-hole shape. Also fixed to, and extending around within, the cap-body 10 at the front of the cap to cover and normally conceal the holes or openings 15, is a sweat band 16 of leather or other suitable material.

The ear and neck protecting section, which may for brevity be designated the ear-protecting section, comprises a body-portion 17 having preferably the shape and marginal contour illustrated in Figs. 2 and 3 to cover the ears and back of the head and neck when separably attached, as hereinafter appearing, to the cap-body. This portion 17 may be of any suitable flexible material and preferably includes an outer piece of material 18 which matches or corresponds with the material of body 10 and an inner piece 19 of material 19 of soft, woolly texture comfortable and warmth-providing to the ears and head. Sewed or otherwise fixed to, and extending continuously along, the upper marginal edge of the portion 17, is a piece 20 of cloth or other relatively thin flexible material preferably folded upon itself at its upper or free end, and throughout its length to form an elongated longitudinally disposed pocket or casing, as at 21. Fitting lengthwise in the pocket 21 with its opposite ends extending outwardly therebeyond, as at 22—22, and securely fixed to the pocket 21 by thread-stitches or the like 23, is a strip 24 of whale-bone or other suitable pliable material. Normally the pocket 21 and its attached strip 24 are folded downwardly to extend lengthwise along the outer face of the flexible piece 20 and above the body-piece or portion 17.

When it is desired to employ the ear-protecting section with the cap proper, the pocket or casing 21 and its attached strip 24 are placed or inserted between the cap-body 10 and its stiffened band 11 and the project-

ing ends 22—22 of the strip fitted to removably extend inwardly of the cap through the opposite transverse band-holes 15—15, as illustrated in Fig. 5, the ear-protecting section being then supported by, and depending in ear and neck covering position from, the band 11 of the cap proper, as seen in Fig. 3, and the band 16 covering, and protecting the head from engagement with, the inserted strip-ends 22—22. The ear-protecting section, including its attaching-strip 24, being easily flexible, readily accommodates itself to the shape of the cap and to the contour of the wearer's head, and it may be here stated that, while with the ear-protecting section so attached to the cap proper, the normal head-size of the cap is slightly reduced, due to the interposition between the head and the cap-band 11 of the flexible piece 20, such slight reduction in head-size is not sufficient to cause the wearer any discomfort, but is sufficient, and is utilized, to cause the ear-protecting section to tightly hug and thereby protect the ears, back of the head, and neck of the wearer. The outer-piece of the body 17 of the ear and neck protecting section being preferably, as stated, of the same material as the cap-body 10, the section, when in cap-attached position, also harmonizes with, and provides a neat appearing addition to, the cap proper.

When it is not desired to employ the protecting section, the body-portion 17 of the section may, as will be evident, be readily folded within the interior of the cap-body 10, the strip 24 remaining in position between the cap-body 10 and the band 11 with its ends 22 fitting in the holes 15, or the section as a whole may be quickly detached and removed from the cap body; in either such event, the cap may be worn or used as an ordinary or standard head-covering cap only.

I am aware that changes in the form, construction, arrangement, and combination of the several parts of my new cap may be

made and substituted for those herein shown and described without departing from the nature and principle of my invention.

Having thus described my invention, what I claim and desire to secure by Letters Patent is:

1. A cap comprising a body-portion and a band fixed at a side-margin to, and extending around within, the body-portion, the band being provided with openings disposed at opposite sides of the body-portion, in combination with an ear-protecting section adapted to depend below the margin of said body-portion and provided flexibly at its upper margin with a pliable strip whose opposite ends extend beyond the opposite side margins of the section, the strip being adapted to removably fit between the cap body-portion and band and its extended ends being adapted for projection through said openings in attaching the section to said body-portion.

2. A cap comprising a body-portion and a transversely stiffened band fixed at a side-margin to, and extending around within, the body-portion, the band being provided with openings disposed at opposite sides of the body-portion, in combination with an ear-protecting section adapted to depend below the margin of said body-portion and provided flexibly at its upper margin with a pliable strip whose opposite ends extend beyond the opposite side margins of the section, the strip being adapted to removably fit between the cap body-portion and band and its extended ends being adapted for projection inwardly of the cap-body-portion through said openings in attaching the section to said body-portion, and a second band on the cap-body-portion for covering said openings and the inwardly projecting ends of said strip when said section is attached to the cap.

In testimony whereof, I have signed my name to this specification.

JACOB YANOW.
